UNITED STATES PATENT OFFICE

2,437,663

DEVICE FOR DEPOSITING MATERIAL IN
WELL HOLESJames D. Haynes, Kilgore, Tex., assignor to The
Dow Chemical Company, Midland, Mich., a
corporation of Delaware

Application November 16, 1944, Serial No. 563,681

2 Claims. (Cl. 166—19)

1

The invention relates to a device, particularly adapted for lowering quantities of pulverulent or granular materials, such as gravel, into deep wells.

One of the objects of the invention is to provide a dumping bailer for use in wells capable of handling a granulated material having a high angle of repose. Another object is to provide a bailer of simple construction and capable of releasing its contents by manipulation of the suspending cable at the top of the well. Another object is to provide a device of the aforesaid character in which the release of the pulverulent material from the bailer is assured. Still other objects and advantages of the invention will appear as the description proceeds, the accompanying drawing and following description setting forth in detail a mode of practicing the invention.

In the drawing:

Figure 1 is a side elevation of the complete bailer assembly largely in cross section attached to a set of jars on a suspending cable.

Figure 2 is a cross section on the line 2—2' of Figure 1.

Figure 3 is a cross section on the line 3—3' of Figure 1.

Figure 4 is a cross section on the line 4—4' of Figure 1.

Figure 5 is a fragmentary view in side elevation of the upper portion of the bailer of Figure 1 taken at right angles to it.

Figure 6 is a fragmentary view in side elevation of the lower portion of the bailer of Figure 1 at right angles to it.

In the several figures, like numerals refer to like parts.

Referring more particularly to the drawing, the bailer comprises a cylindrical container 1 having a diameter slightly less than the well it is to enter. The top is provided with an opening as at 2 while side portions 3 extend upward to support the guide ring 4. The bottom is similarly constructed with openings 5 and side extensions 6 supporting the foot 7. The bottom of the container is closed by a removable disc 8 supported on shear pins 9 inserted through holes 10 in the wall of the container. The shear pins may consist of heavy gauge wire, the ends 11 being bent over as shown to hold them in place.

The interior of the container is provided with an agitator consisting of a tubular member 12 extending substantially the length of the cylindrical portion of the container. The lower portion of the agitator is provided with guides 13 adapted to center the agitator while allowing

longitudinal movement in the container. The bottom end is provided with a reinforcing ring 14. Secured in the upper end of the agitator is a ring 15, having an opening through which a bar or rod 16 extends in a sliding fit. The lower end of the rod 16 carries a stop 17 adapted to engage reinforcing ring 14 so as to prevent the rod from being upwardly pulled through the tube 12. Guide members 18 attached to the inner 10 surface of the container near the upper end serve to centralize the upper end of the tubular member 12 in the container. Above the ring 15, a stop 19 is provided on rod 16 so as to limit its downward movement relative to the tube 12 by engagement with the ring 15. The stop member 19 affixed to the rod 16 limits the upward travel of the rod 16 relative to the container by engaging the bottom of ring 4. The upper end of the rod 16 is screwed into a coupling 20 which is connected to the shaft 21 of jars 22, attached to cable socket 23 to which is attached the suspending cable 24.

In operation, the bailer assembly, exclusive of the jars, is lowered into the well on cable 24 leaving the top opening 2 exposed above the well so that the bailer container 1 may be filled with the material to be dumped into the well. Prior to the lowering of the bailer in the well closure disc 8 is inserted in the bottom of the bailer and shear pins 9 set in place so as to support the disc, and the agitator positioned to rest upon stop 17 while the latter is positioned close to the disc 8 as shown. The bailer cylinder 1 is then loaded as by pouring the material thereinto 30 through the top opening 2. The loaded bailer is then let down into the well on the jars and cable until the foot member 7 rests upon the bottom or such filling material as may be therein.

To unload the bailer, the cable is raised and lowered alternately in amount sufficient to operate the jars. The resulting downward movement of the rod 16 drives the stop member 17 upon the disc 8 which in turn breaks the shear pins 9 allowing the disc 8 to fall out of the opening 45 5 into the well.

The discharge of the container 1 is then effected by raising and lowering the cable so as to raise and lower the agitator tube 12 inside the container, this vertical movement serving to bring 50 about the release of the pulverulent material in the annular space between the tubular member 12 and wall of the container 1. As the agitator is being thus raised and lowered and the pulverulent material leaves the bailer container and 55 enters the well, the bailer assembly is raised cor-

respondingly so as to allow the pulverulent material to settle in the well below the foot member 7, the raising of the bailer container being continued alternately with lowering the same so as to both agitate the contents of the bailer by longitudinal movement of the agitator 12 and raise the container off the accumulative pulverulent material in the well bore as the latter fills.

I claim:

1. A dumping bailer adapted for lowering a pulverulent material into a well comprising a container for holding the pulverulent material to be dumped, a removable closure in the bottom of the container, shear pins in the bottom of the container adapted to form a support for the closure and to release the closure when sheared, a central agitator longitudinally disposed within the container and adapted for longitudinal motion therein, guide means attached to the lower end of the agitator for centralizing the lower end of the agitator within the container, a bar extending longitudinally through the agitator, upper stop means on the upper end of the bar limiting downward movement thereof relative to the agitator, lower stop means on the lower end of the bar limiting upward movement thereof relative to the agitator, said bar being of sufficient

10 15

length between the said upper and lower stop means to permit longitudinal movement of the bar relative to the agitator so that the lower end of the bar may strike the removable closure, stop means attached to the upper end of the container for limiting the upward movement of the bar by engaging the upper stop means thereon, and means attached to the upper end of the bar above the upper stop means for suspending the container in the well.

2. A dumping bailer according to claim 1 and having a guide means in the upper end of the container for centralizing therein the upper end of the agitator.

JAMES D. HAYNES.
